United States Patent Office.

FREDERICK LEIBRANDT AND WILLIAM L. McDOWELL, OF PHILADELPHIA,
PENNSYLVANIA.

Design No. 2,970, dated March 31, 1868.

DESIGN FOR A STOVE.

The Schedule referred to in these Letters Patent and making part of the same.

TO ALL WHOM IT MAY CONCERN:

Be it known that we, FREDERICK LEIBRANDT and WILLIAM L. McDOWELL, of the city of Philadelphia, in the State of Pennsylvania, have invented or produced a new and original Design for a Stove, of which the following is a full and exact description, reference being had to the accompanying drawing, making a part of this specification, and to the letters of reference marked thereon.

This is a portable stove for heating chambers, &c., and is designated by name "Sun," as shown in the drawing.

Our invention or production consists of the forms and configurations of all the parts A, B, and C, below the faint line *xy* of the drawing.

What we claim as our invention, and desire to secure by Letters Patent, is—
The design for a stove, herein set forth and shown.

FRED'K LEIBRANDT,
W. L. McDOWELL.
